UNITED STATES PATENT OFFICE.

LOUIS MARCELLUS WOOD, OF NEW YORK, N. Y., ASSIGNOR TO SPEED-O MULTIPLE VALVE LIFTER CORPORATION, OF NEW YORK, N. Y., A CORPORATION OF NEW YORK.

LIFTER FOR VALVE SPRINGS.

Application filed January 4, 1924. Serial No. 684,272.

This invention relates to lifters adapted for the purpose of lifting or elevating under compression a plurality of valve springs in internal combustion engines, and more particularly to lifters adapted to simultaneously lift a multiple number of valve springs, an object of the invention being to provide an improved valve spring lifter which will be relatively simple in construction, relatively easy and cheap to manufacture, and so constructed that a number of valve springs may be elevated under compression with a minimum of effort and without the exertion of any considerable amount of strength.

A further object of this invention is to provide a valve spring lifter having improved cam means for lifting the valve springs of the engine under compression whereby in operation the force exerted by the cam means will be so applied and directed as to elevate the lifting member in a substantially straight vertical plane, thereby limiting any material tendency of the lifting member to move or shift relatively to the valves during operation.

A further object of this invention is to provide an improved valve spring lifter wherein the lifting member and cam means for operating the same are so interconnected as to cause the lifting member to be guided against transverse movement through the medium of the cam means.

A further object of this invention is to provide a valve spring lifter having improved cam means for operating the lifting member, and wherein the cam means is so located with respect to the lifting member and so constructed as to enable a multiple number of valve springs to be simultaneously elevated and without any material tendency of the lifting member to shift in transverse directions relatively to the valves during operation.

Other objects of this invention will appear in the following description and appended claims, reference being had to the accompanying drawings forming a part of this specification wherein like reference characters indicate corresponding parts in the several views and wherein Fig. 1 is a front elevation illustrating an embodiment of my invention in operative position; Fig. 2 is a sectional side elevation taken substantially on line 2-2 of Fig. 1; Fig. 3 is a fragmentary sectional side elevation taken on

line 3-3 of Fig. 1 and illustrating the valve springs in lifted position; Fig. 4 is a perspective view illustrating a present embodiment of my invention; Fig. 5 is a perspective view of a cam member; Fig. 6 is a fragmentary longitudinal section taken through the cam block and illustrating the position of one of the cams with the lifting member in elevated position, and Fig. 7 is a transverse section taken substantially on line 7-7 of Fig. 6.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

The present improved mechanism for elevating or lifting under compression the several valve springs of the engine is of course, adapted to be used in connection with various types of engines, and although one form of engine is herein illustrated by way of example it is obvious that the mechanism may be adapted to other engines having different numbers of cylinders. It is also understood that the form and design of the mechanism may be altered in order to adapt the mechanism to different engines having different forms and arrangement of parts.

Referring to the drawings wherein a present preferred form of my invention is shown, it will be seen that the engine block is provided with the usual valve spring chamber 9 which is adapted to be closed at the front thereof with a suitable cover or door plate (not shown). The cover plate in the engine illustrated herein by way of example is held in position by means of a fixed bolt or stud 50 having a nut 51 adapted to be screwed on to the outer end of the bolt or stud. In some instances the cover or door plate is held in position by means of a bolt or stud which is headed at its outer end and adapted to be screwed into the rear wall of the valve spring chamber. The valve spring chamber 9 is located within a housing or casting comprising rear cylinder walls 10 and forwardly extending end walls 11. The front of the valve spring housing is also provided with a depending lip 12 and also

with the usual upwardly projecting lip or flange 13 extending along the lower edge thereof and against which the cover or door plate is normally bolted. The valves 14 are 5 provided with valve stems 15 which extend into the chamber 9, and adjacent to the lower ends of the valve stems are located retaining pins 16 against which the valve spring retaining seats 17 impinge when the 10 valve springs are in normal position, the seats or retainers 17 being constructed to receive the lower ends of the valve springs 18 which are held between the retainers and the upper wall of the chamber 9. The bottom of the valve spring housing is provided 15 with the usual guide members or bearings 19 through which the valve lifters 20 extend, the latter being operated by cams on the cam shaft of the engine for the purpose of 20 operating the valves.

The valve lifter in the present instance is preferably in the form of an angle bar which may be readily made in a single casting, the angle bar comprising a vertically extending member 21 and a horizontally extending member 22. The part 21 of the angle bar extends across or in front of the four valves and valve springs, and the horizontal part 22 of the bar forms a means adapted to 25 extend beneath the valve springs and retainers for operating thereagainst. Centrally of the lifter the member 21 is provided with a rearward extension or enlarged portion 23, and the member 22 is provided 30 with an enlarged portion 24, the parts 23 and 24 being cast integrally. The central enlarged portion 23 of the lifting member is provided with a vertical guide slot 25 which 35 communicates with a horizontally extending slot or groove 26 formed in the central extension 24 of the lifting member. The purpose and function of the slots 25 and 26 are to receive the housing bolt 50 and to permit the 40 lifting member to be guided by such bolt 45 against endwise movement relatively to the valve springs, and also to enable the lifting member to be readily positioned with relation to the valve springs.

The rear face of the central portion 23 of 50 the lifting member is recessed at 27, and at the bottom of such recess a pair of projections or abutments 28 are formed, the projections 28 being located at opposite sides of the guide slot 25. These projections are 55 bored to permit the passage therethrough of the guide screws as hereinafter described.

The horizontal member 22 of the lifter is provided at suitable intervals with rearwardly extending slots or recesses 29 into 60 which the valve stems extend, the sides of the recesses 29 forming seats for the valve spring retainers 17.

It will be noted that the valve spring recesses 29 extend rearwardly the full width 65 of the horizontal member 22, and that these

recesses or slots terminate at the rear thereof in vertically extending recesses 30 formed in the vertical member 21 of the lifting bar. It will be seen that an important advantage is derived for forming the valve spring recesses 29, 30 in this manner, since it is possible for the operator after the valve lifter has been elevated against the valve springs to insert the fingers for the purpose of removing the pins 16 or replacing them. 70 75

The lifting member in the present instance is operated by a cam means which comprises a suitable supporting block 31 having a transversely extending slot or groove 32 for receiving a rotatable spindle 33. The spindle 33 is provided with a pair of spaced cams 34, each cam at one side having a curved working face 35 terminating in an approximately flat face 35^a. It will be seen that the spindle 33 carrying the spaced cams has a bearing in the cam block 31 and is adapted to be rotated for the purpose of swinging the cams from a horizontal to a vertical position, and vice versa, by means of a suitable wrench 52 which may be inserted over the squared end 37 of the spindle or shank 33. It will be noted that the transverse slot or recess 32 is open at the top thereby permitting the spindle 33 to be readily inserted therein and removed. 80 85 It will also be noted that the supporting block 31 is provided at one side with a pair of spaced slots 31^a for receiving and housing the cams 34 when the latter are shifted downwardly into the position shown in Fig. 4, thereby causing the lifting bar to rest upon the upper face of the cam block when in lowered position. 90 95

At opposite sides of the spindle 33 the cam block 31 is tapped to provide a pair of holes into which are screwed a pair of guide screws or pins 38, these screws extending freely through holes in the projections 28 and in the extension 24. Between the heads of the screws 38 and the upper faces of projections 28 are located a pair of coiled springs 39. These springs function normally to force the upper face of the cam block 31 against the lower face of the extension 24, thus holding these parts together 100 rigidly when the lifting device is not in use and when it is being placed in position under the valve springs. 105 110

In using the present valve lifter the nut 51 is unscrewed from the end of the stud bolt 50 and the cover or door plate for the valve spring housing removed. The angle bar is then slipped over the stud bolt 50, it being understood that the latter extends through the guide slot 25 as shown in Fig. 1, whereupon the nut 51 is screwed on to the end of the bolt 50 sufficiently to hold the valve lifter in proper position. The wrench 52 is inserted over the squared end 37 of spindle 33, and by manipulating the wrench 115 120 125 130

the spindle 33 may be readily rotated a quarter turn so as to swing the cams 34 from a horizontal position to a vertical position as shown in Figs. 6 and 7. It will be noted that the spaced cams 34 operate directly beneath and in line with the valve springs, as shown in Fig. 3, or in other words the vertical plane extending centrally through the longitudinal axis of all of the valve springs will also extend centrally between the cams 34 so that the force exerted by the cams will be transmitted on a direct line with the valve springs, thus minimizing any tendency of the lifting member to operate other than in a straight vertical plane against the springs.

It will be further seen that the combined vertical and horizontal guide slot 25, 26, will provide a guide means adapted to operate with the housing stud or bolt 50 to position the lifting member and also to guide it vertically against any endwise movement relatively to the valve springs.

The cam block 31 is provided with a pair of downwardly projecting lugs 40, which when the cam block is placed in position beneath the valve springs will overlap the front edge 13 of the valve spring housing, and maintain the cam block in position against inward movement relatively to the valve springs. Since therefore these lugs 40 prevent inward movement of the cam block and since the lifting member is guided by the guide pins 38, it will be seen that by means of the guide pins 38 which connect together the lifting member and cam block, the lifting member is vertically guided against inward movement through the medium of the cam block.

It will be seen further that the spaced guide pins or bolts 38 maintain the lifting member in horizontal position at all times, and prevent any tendency thereof to oscillate or tilt during operation. Such oscillation or tilting might be caused by variations in the pressure of the springs at opposite ends of the lifter, or by the fact that the cams do not at all times contact at the exact center of the lifter. The bolts 38 and springs 39, which function together as spring plungers normally hold the lifting member and cam block together and detachably interlock the parts, since the cam block and lifting member may be readily detached one from the other by unscrewing the bolts.

From the foregoing construction it will be noted therefore that effective and efficient operation of the present valve lifter is obtained, since the guide slots 25, 26 in conjunction with the housing bolt 50 guide the lifting member in operation against endwise movement, and since the camming means by virtue of parts 40 and guide means 38 guides the lifting member against inward movement relatively to the valve springs,

and since the spaced cams 34 operate against the underface of extension 24 of the lifting member at points equidistant from the vertical plane extending through the longitudinal axis of the valve springs.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A valve spring lifter comprising a lifting member, a supporting member extending transversely beneath said lifting member, a shiftable cam carried by said supporting member and shiftable into engagement with the lifting member for elevating the same and means located in rear of said cam for slidably connecting the lifting member and supporting member together.

2. A valve spring lifter comprising a lifting member, a supporting member extending transversely beneath said lifting member, a shiftable cam carried by said supporting member and shiftable into engagement with the lifting member for elevating the same and a spring carrying member located in rear of said cam for slidably connecting the lifting member and supporting member.

3. A valve spring lifter comprising a lifting member, and cam means operative beneath said member for elevating the same, said cam means having depending projecting means adapted to engage a part of the engine for maintaining the cam means against predetermined shiftable movement, and guide means for guiding said lifting member from said cam means, said cam means comprising a pair of shiftable cams spaced transversely to said lifting member.

4. In a valve spring lifter, the combination of a lifting bar constructed to simultaneously cooperate with a plurality of valve springs, a supporting block located below and at the middle of the length of said lifting bar, means for shiftably connecting said lifting bar with said block, and rotatable cam means located directly above the supporting block and below the lifting bar and pivotally supported therebetween crosswise of the lifting bar and operative on the rotation thereof to lift said lifting bar relative to said supporting block.

5. A valve spring lifter comprising a lifting member, cam means for elevating said lifting member, means for guiding said member from said cam means, and resilient

- means for normally maintaining said member and cam means together.
6. In a valve spring lifter, the combination of a lifting bar constructed to simultaneously cooperate with a plurality of valve springs, a supporting block located below said lifting bar, means for shiftably connecting said lifting bar with said block, and rotatable cam means located above the supporting block and below the lifting bar and pivotally supported therebetween crosswise of the lifting bar and operative on the rotation thereof to lift said lifting bar relative to said supporting block, said cam means comprising a plurality of cams spaced transversely of the lifting bar.
7. A valve spring lifter comprising a lifting member, a support, a spindle carried thereby and having a wrench-engaging portion and a pair of spaced cams carried by said spindle, said cams being in position and operating as a unit against the lifting member directly under the line of engagement of the lifting member with the bottoms of the valve springs thereby to elevate the lifting member whereby the action of the cams is exerted directly under and between the margins of the springs.
8. A valve spring lifter comprising a lifting member, a support, a cam carried thereby for elevating said lifting member and a spring carrying member connecting said lifting member and support.
9. A valve spring lifter comprising a lifting member having means adapted to extend beneath a plurality of valve springs, said member having centrally thereof a vertical slot adapted to receive an engine stud or bolt, a support, and a cam carried thereby for elevating said member, said support being connected centrally to said lifting member.
10. A valve spring lifter comprising a lifting member having a vertically extending guide slot adapted to receive a housing stud or bolt, cam means operative adjacent to said slot for elevating said member, and guide means for connecting said cam means and member together.
11. A valve spring lifter comprising a cam block having a transverse recess, a rotatable spindle having a bearing in said recess, a pair of spaced cams carried by said spindle, and a lifting member controlled by said cams.
12. A valve spring lifter comprising a cam block having a transverse recess, a rotatable spindle having a bearing in said recess, a pair of spaced cams carried by said spindle, and a lifting member controlled by said cams, each of said cams having at one side a curved working face terminating in an end portion having a working face of less curvature.
13. A valve spring lifter comprising a lifting member having a guide slot adapted to receive the housing stud or bolt of the engine, cam means for elevating said member, and guide means located at opposite sides of said guide slot for connecting said cam means and member together.
14. A valve spring lifter comprising a lifting member having a guide slot adapted to receive the housing stud or bolt of the engine, cam means for elevating said member, and guide means located at opposite sides of said guide slot for connecting said cam means and member together, said guide means having springs for maintaining said member and cam means in predetermined position.
15. A valve spring lifter comprising a lifting member, cam means for elevating the same, and guide means connecting said cam means and member together and located in rear of said cam means.
16. A valve spring lifter comprising a lifting member, a support, a cam carried thereby for elevating said lifting member, and a pair of spaced guide members connecting said support and lifting member in rear of said cam.
17. A valve spring lifter comprising a lifting member, a support, a cam carried by said support for elevating the lifting member, and a guide pin slidably connecting said support and lifting member and detachably connected to one thereof.
18. A valve spring lifter comprising a support, a shiftable cam carried thereby for elevating the lifting member, and a vertical member slidably connecting said support and lifting member and having a detachable threaded connection with one thereof.
19. A valve spring lifter comprising a vertical member and a horizontal member, a cam block located beneath said horizontal member, a shiftable cam carried by said block and adapted to operate against the under face of said horizontal member, a guide pin carried by said cam block and extending through said horizontal member.
20. A valve spring lifter comprising a vertical member and a horizontal member, said vertical member having a guide slot, cam means located beneath said horizontal member and adapted to operate thereagainst for elevating the same, a pair of guide pins carried by said cam means and extending through said horizontal member at opposite sides of said guide slot.
21. In a valve spring lifter, the combination of a lifting member, a cam support, a rotatable spindle carried thereby, a cam carried by said spindle for elevating said lifting member, said support having an open slot permitting removal of said spindle.
22. In a valve spring lifter, the combination of a lifting member, a cam support having a transverse recess open at the top, a ro-

tatable spindle journaled in said recess and a cam carried by said spindle for elevating said lifting member.

23. In a valve spring lifter, the combination of a lifting member, a cam support having a transverse recess and a pair of spaced recesses communicating with said transverse

recess, a spindle journaled in said transverse recess, and a pair of spaced cams carried by said spindle and adapted to be shifted into and out of said spaced recesses. ¹⁰

Signed at New York city, N. Y., this 17th day of December, 1923.

LOUIS MARCELLUS WOOD.
